UNITED STATES PATENT OFFICE.

CONRAD EGGE, OF ROSLINDALE, ASSIGNOR TO THE TOWLE MANUFACTURING COMPANY, OF NEWBURYPORT, MASSACHUSETTS.

DESIGN FOR A SPOON-HANDLE.

SPECIFICATION forming part of Design No. 13,613, dated February 13, 1883.

Application filed December 21, 1882. Term of patent 7 years.

To all whom it may concern:

Be it known that I, CONRAD EGGE, a citizen of the United States, residing at Roslindale, in the county of Norfolk, of the State of Massachusetts, have invented and produced a new and original Design for Spoon or other Handles; and I do hereby declare the same to be described in the following specification and represented in the accompanying drawing, 10 which is a top view of a spoon having upon its handle the said ornamental design.

The upper part or section, A, of the design is a plain shield, *a*, having a form as shown, and surrounded by a border, *b*, in the form substantially like that of a horseshoe-magnet, the said border being beaded at its edges by beads *c c*, and having its surface between them studded or embossed with flowers, as shown. The next section, B, is a tapering 15 shield, beaded at its edge or border, and hav-

ing stamped in relief upon it a stem with leaves, a flower, and buds, as represented. The next and last section, C, is on what may be termed the "shank" portion of the handle, and, besides having beaded edges, it has in relief three flowers, with two leaves to each, and above the upper of such flowers, and between it and the handle-section, an embossing of flowers, all being as and arranged as shown. The flowers above mentioned are daisies. 25 30

I claim—

The design, substantially as described, for a spoon or other handle, it consisting of the three sections A, B, and C, their beadings or borders, and embossed flowers and leaves, as 35 and arranged substantially as represented.

CONRAD EGGE.
